UNITED STATES PATENT OFFICE.

BERTHA MULCAHY, OF SAN JOSE, CALIFORNIA.

HAT-FASTENER.

No. 855,722.

Specification of Letters Patent.

Patented June 4, 1907.

Application filed August 16, 1906. Serial No. 330,871.

To all whom it may concern:

Be it known that I, BERTHA MULCAHY, residing at the city of San Jose, in the county of Santa Clara, in the State of California, 5 wife of M. Vincent Mulcahy, physician, a citizen of the United States of America, residing at the city of San Jose aforesaid, have invented a new and useful Hat-Fastener, of which the following is a specification.

10 My invention pertains to hat fasteners—*i. e.*, devices for fastening ladies' hats to the hair; and it has for its object to provide a fastener embodying such a construction that with a single manipulation the device may 15 be secured in any hat, and the hat secured on the head in such manner that there is no liability of the hat tilting, and one provided with means whereby its head is stopped at such a distance from the hat that said head 20 may be readily grasped when it is desired to withdraw the fastener from the hair and hat.

With the foregoing in mind the invention will be fully understood from the following description and claim when the same are 25 read in connection with the accompanying drawings, forming part of this specification, in which:

Figure 1 is a detail view of the two-prong pin comprised in my novel hat fastener. 30 Fig. 2 is a view illustrative of the manner in which the pin is attached to the head of the fastener, and: Fig. 3 is a view illustrating the fastener complete and ready for use.

Similar letters designate corresponding 35 parts in all of the views of the drawings, referring to which:

A is the pin of the hat fastener. The said pin is made of one piece of wire or other material consonant with the purpose of the invention and comprises two parallel prongs 40 *a* and *b*, arranged about the proportional distance illustrated apart, and a cross-bar *c* extending between and connecting adjacent ends of the prongs. At their ends remote 45 from the cross-bar *c* the prongs *a* and *b* are preferably pointed as illustrated to facilitate their being forced into and through the material of a lady's hat.

B is the head of the fastener to which the 50 pin A is connected, and C is the band or collar which receives the prongs *a* and *b* of the pin and is positioned on said prongs at a point adjacent to the head B, as shown in Fig. 3. The connection of the pin A to the 55 head B is a pivotal one, and is effected

through the medium of a metallic attaching plate *d* which is soldered or otherwise affixed to the head and is provided with a barrel *e* in which the cross-bar *c* of the pin A is journaled. The head B is preferably of metal; and it 60 may have any desired configuration and be made thick or thin in the discretion of the manufacturer without involving departure from the scope of my invention as claimed.

In the practical use of my novel fastener, 65 the prongs of the pin A are forced into and through one side of a hat, the hair of the wearer and the opposite side of the hat in the order named until the band or collar C brings up against the exterior of the first mentioned 70 side of the hat, and when the fastener is thus arranged, it will be apparent that the prongs *a* and *b* of the pin will rest in parallel positions, and will consequently prevent tipping of the hat as on a pivot or in other words will 75 assure stability of the hat on the head. It will also be apparent that the head B may be made flat or of a curvature to conform with the shape of a hat for when the fastener is forced to its working position, the band or 80 collar C will engage the exterior of the hat and by serving as a stop will assure the head B being put into such a position, relative to the hat, that said head may be conveniently grasped when it is desired to withdraw the 85 fastener from the hat. In addition to engaging the exterior of the hat and serving to stop the head B from said exterior, the band or collar C serves by snugly surrounding the prongs *a* and *b* to materially strengthen the 90 connection between the heel portions of the said prongs and to retain the same in positions parallel to each other so as to prolong the usefulness of the hat fastener as a whole. By virtue of the head of the fastener being 95 ornamental in appearance, the fastener may be applied at any desired point relative to the hat; it being understood that hats according to shape require fastening at one of three points, *viz*: back, side or front. 100

In addition to the advantages hereinbefore ascribed to my novel hat fastener, it will be noticed that the fastener is susceptible of being easily and cheaply produced; also, that the fastener is calculated to enhance rather 105 than detract from the finished appearance of a hat, and that it is well adapted to withstand the usage to which hat fasteners are ordinarily subjected.

Having described my invention, what I 110

claim and desire to secure by Letters-Patent, is:

As an article of manufacture, a hat fastener comprising a pin formed of one piece of material and having parallel prongs joined at their rear ends by a cross-bar, a head, an attaching plate fixed to the inner side of the head and having a barrel in which the cross-bar of the pin is journaled to pivotally connect the pin with the head, and a band or collar arranged on and snugly receiving the

prongs of the pin at a point adjacent to the attaching plate, whereby said band or collar is adapted to serve as a stop and also to tie the prongs together to strengthen the connection between the same without interfering with the head swinging on the pin. 15
